CLYDE V. GUSTIN, OF MONETT, MISSOURI.

ROLLER-SKATE.

1,271,891.

Specification of Letters Patent. Patented July 9, 1918.

Application filed February 14, 1918. Serial No. 217,110.

To all whom it may concern:

Be it known that I, CLYDE V. GUSTIN, a citizen of the United States, residing at Monett, in the county of Barry and State of Missouri, have invented certain new and useful Improvements in Roller-Skates, of which the following is a specification.

This invention relates to skates, and more especially to those having rollers instead of runners, and the object of the same is two-fold. First, my object is to provide the skate runner with a stop disposed out of the transverse center of the skate and forward of its foremost roller so that when the user tips his rearward foot inward in the act of making a stroke by causing his forward foot to glide over the floor, the stop engages the same to enable him to push or impel himself forward. Second, I propose to make use of a new form of roller which is in effect a sphere mounted in ball bearings, and several types of the latter are shown.

The following specification sets forth ample means for carrying out both ideas, and reference is made to the drawings hereto attached and in which:

Figure 1 is a bottom plan view of the left skate, partly in section,

Fig. 2 is a central longitudinal section through the same, and

Fig. 3 is a transverse section on the line 3-3 of Fig. 2.

Fig. 4 is a vertical section of a slightly different form of roller.

Fig. 5 is a bottom plan view of the left skate with a different form of stop.

Instead of a runner as in an ice skate or a base having bearings in which wheel-like rollers are mounted, I make the runner of this skate substantially in the shape of the sole of the shoe in contour, preferably of wood, and of considerable thickness. The runner is designated in the drawings by the numeral 1, and its upper face at its forward portion is dished as at 2 to

receive the shoe-sole while its rear portion is recessed as at 3 to receive the heel. The means for fastening this runner to the shoe are not shown, as they form no part of the present invention. This runner-like block has an offset 4 from its inner edge just in rear of its toe, and in Fig. 1 this offset is shown as containing a recess 5 within which is journaled a roller moving in a plane strictly parallel to the longitudinal line of the runner. The runner 1 shown in

Fig. 5 has the same offset, but in place of the recess and roller, it has a rubber pad 7 either secured to or depending from the runner or mounted fixedly in a recess 60 therein. Either element constitutes what I call a stop, and depends below the lower face of the runner to an extent best seen in Fig. 2. The purpose of this feature will be explained in detail below.

Instead of having the wheels or rollers in direct alinement along the transverse center of the runner, I preferably use three wheels or rollers, disposing two of them under the ball of the foot and one directly under the heel, although this is not absolutely necessary. The rollers in the present instance are shown in the form of spheres 10, each mounted in ball bearings within appropriate sockets in the material of the runner. 70 These balls 11 are shown in Figs. 2 and 3 as occupying zones 12 which are in the shape of annular balls races surrounding the spheres at different heights. The balls 11 in Fig. 4 are shown as mounted in arcuate 80 races 13 and 13', preferably standing at right angles to each other as indicated, and each race is lined with metal as indicated at 14. The balls or spheres are also preferably metal and of considerable size, but 85 whatever the character of the ball bearings by which they are supported, the lower sides of the spheres project below the lower face of the runner as seen in Fig. 2 at 16 to a greater distance than does the lower side of 90 the stop 6 project below said face. The result is that when the user rests his foot squarely on the rollers, his weight is sustained by them and the stop is not in contact with the surface. This is true 95 whether there are three rollers or two and whether the rollers are wheels or spheres as shown. The advantage of ball bearing rollers or spheres over those having ordinary bearings is too well known to need repetition here.

A roller skate embodying both these features of improvement possesses the following advantages: The skater may use it as usual, and in addition he may stand 105 squarely on both feet or on either foot, because each foot has three points of support; and this is especially useful where the skater has a weak ankle. When gliding forward, all rollers are kept in contact with the surface while the foot is making its stroke, but when skating more rapidly and the user

wants to push with the rear foot, the advantage of having the stop becomes apparent. Now while the right foot is forward and the left foot to the rear and to one side of the 5 line of progress, the skater tips his foot inward a little so that the stop is thrown into contact with the surface, and then pushing transversely of the foot, he impels himself forward. Such is the operation whether the 10 stop is a roller as shown in Fig. 1 or a pad or plug of rubber as shown in Fig. 5, and in fact the roller might itself be rubber. When proceeding straight forward, if the roller should touch the surface it will simply rotate whereas the pad would become 15 worn if it touched the surface, but when the foot is tilted as described and either the roller or the pad brought into contact with the surface and is pushed transversely of the 20 foot, the skater is impelled forward as has been explained. This result follows whether there are three rollers in the runner or two, but it is necessary that the stop should be disposed transversely out of alignment with 25 the transverse center of the runner. Also it is advisable that the stop shall be disposed forward of the foremost roller, so that if he desires to do so the skater may at any time tilt his toe downward a little and throw the 30 stop into contact with the surface. If the stop be of the pad type shown in Fig. 5, it now acts as a brake. Again, braking effect may be reduced if the operator cant's his toe upward slightly and drags the heel end or

rear end of the runner on the surface. These 35 several possibilities follow from the fact that the lower end of the runner travels so near the surface which is permitted by embedding the sphere-like rollers into the block or element constituting the runner rather 40 than mounting them in bearings beneath said block as in the ordinary type of roller skate.

What is claimed as new is:—

In a roller skate, the combination with a 45 block-like runner conforming on its upper face with the shape of the shoe-sole, having an offset at the inner forward side thereof, the offset provided with an upright recess parallel with the longitudinal axis of the runner and opening at its lower face, said lower face being flat and provided with sockets surrounded by ball races; of balls in said races, spheres mounted in said sockets and projecting below the lower face of said 50 blocks, and a roller mounted in said recess and projecting also below said lower face a less distance than the spheres, two of the latter being provided at opposite sides of the longitudinal axis of the block and in 55 rear of said roller, and a single sphere under the heel.

In testimony whereof I affix my signature in presence of two witnesses.

CLYDE V. GUSTIN.
